UNITED STATES PATENT OFFICE.

JAMES MADISON MILLER, OF WASHINGTON, DISTRICT OF COLUMBIA.

SILENCER.

981,584.

Specification of Letters Patent. Patented Jan. 10, 1911.

Application filed October 15, 1910. Serial No. 587,163.

To all whom it may concern:

Be it known that I, JAMES MADISON MILLER, a citizen of the United States, residing at Washington, District of Columbia, have 5 invented certain new and useful Improvements in Silencers, of which the following is a specification.

The invention relates to an improvement in silencers constructed and arranged for use 10 with gas engines with the effect to dissipate the energy of the exhaust gases by counter-acting their velocity of movement and changing their path of direction while within the silencer.

15 The main object of the present invention is the provision of a silencer in which the body of gas in its travel lengthwise of the silencer is successively divided into a series of rotary or whirling currents to reduce the 20 velocity of movement of the gas and dissipate the energy, the whirling current being directed in a direction opposed to that of their original path of travel within the silencer and delivered into an enveloping or 25 collection chamber in which their direction of movement is again changed and from which the gases finally escape under the power of the expansion force alone, thereby insuring a silent discharge.

30 Another object of the invention is the provision of a silencer in which the deflecting planes are of continuously increasing diameter from the inlet to the discharge end of the silencer, the final deflecting plane 35 forming a complete obstruction to the passage of the gas in its normal path centrally of the silencer, the relative proportion of sizes of the deflecting plane serving to cause each plane to take care of its proper proportionate part of the gases passing through 40 the silencer, with the effect to equalize the distribution of the gases and avoid any back pressure interference with the gas stream entering the silencer. The regular distribution 45 of the gases within the silencer necessarily tends to the formation of a pull upon the gases in the main stream or path with the effect to create a vacuum at the inlet end of the silencer and not only avoid back pressure on the engine, but actually induce a 50 vacuum pull and scavenging effects on the cylinders.

Another object of the invention is the pro-

vision of a muffler in which the gases after being influenced by the deflecting surfaces 55 or planes are collected in an enveloping casing from which they are discharged by their expansive force, whereby the volume of gas affected by each deflecting surface is by said surface directed into the casing wholly beyond the influence of the succeeding deflecting surfaces. 60

The invention will be described in the following specification, reference being had particularly to the accompanying drawings, 65 in which:—

Figure 1 is a vertical section of the improved silencer. Fig. 2 is an enlarged perspective view illustrating two of the deflecting units or cups in coupled relation. Fig. 70 70 3 is an enlarged broken sectional view, illustrating particularly the different currents in the silencer. Fig. 4 is a broken sectional view showing a modified arrangement of and connection between the deflecting cups. 75

Referring particularly to the accompanying drawings, the improved silencer is made up primarily of a series of deflecting elements or cups 1, including cup like bodies having edge flanges or walls 2 and bottom walls 3. The edge walls are of fluted conformation longitudinally providing, in transverse section a series of oppositely opening channels, that is, channels 4 opening to the interior of the cup and channels 5 80 opening to the exterior thereof, said channels being alternately disposed, as more clearly shown in Fig. 3. The bottom wall is a double concavo-convex form, that is, concaved on the inner surface and convex on 85 the outer surface, having the meeting lines of curvature at approximately the central point of the bottom, so that from said central point the bottom curves in all directions toward the side wall. The bottom of each 90 cup member, except the final one of the series is formed with an opening 6, said opening being centrally disposed and by reason of the formation previously described, the inner surface of the bottom between the edge 95 of the opening and the side wall is regularly concaved throughout as at 7, while the outer surface is convex as at 8.

Cup members are, in the preferred form, secured in assembled or interlocked relation 100 105 by forming each cup at the juncture of the

side wall and bottom with a series of spurs 9 cut from the material and slightly offset therefrom; the interlocking being secured by arranging the spurs of one cup, which spurs 5 are formed in longitudinal alinement with the inwardly opening channels of said cup, to fit the free forward edges of the outwardly opening channels 5 of the next adjacent cup. By this arrangement the cup 10 members when in interlocked relation are arranged so that the mouth or outlet end of each inwardly opening channel 4 longitudinally alines with and directly discharges into an outwardly opening channel 5 of the 15 next adjacent cup. By this means regularly divided paths of travel for the gases from between the cups are provided.

The silencer is provided with an inlet shell 10 of semi-spherical shape formed with 20 a connection 11 for the exhaust pipe 12 from the end, said shell being formed adjacent its outlet end with an annular approximately semi-circular flange 13. An outlet shell 14 is provided for the outlet end of the 25 silencer, said shell having a central opening 15 for the connection of an escape bell or pipe, as 16. The outlet shell is also formed with an annular flange 17 corresponding to the flange 13 of the inlet shell. 30 A collector casing 18, of an appropriate length is arranged between the inlet and outlet shells, the ends of the casing fitting within the annular flanges 13 and 17 of the shells, the latter being reduced, if desired, 35 at 19 to provide an accurate gas pipe fit.

In assembling parts, the cup members are secured in connected relation, as described, any desired number of members being used. The forward edge of the cup member immediately adjacent the inlet shell seats in a 40 recess 20 formed in the shell edge, while the final cup member is engaged by an outlet band 21 formed with a series of elongated openings 22, which openings provide a communication between the collection chamber 18 and the outlet shell 14. The collection chamber has a diameter exceeding the maximum diameter of the cup members and is secured in place by tie-rods 23 passing 45 through the flanges of the respective shells and secured by nuts in an appropriate manner. Tie-rods thereby serve to hold all parts in connected relation.

It will be noted that as previously described, the final cup member is centrally formed without the opening of the remaining cup member, thereby providing an abutment 24 closing the central passage through the silencer. Furthermore, the central opening of the silencer is gradually reduced from the inlet opening to the abutment, while the channels in the annular or side wall of the cup members open toward the inlet end of the silencer.

In Fig. 4, I have shown a slightly modified 65 form of arrangement in which the cup members are not disposed in lapped relation, but are spaced as shown. The parts are secured in connected relation by tie-rods 25 passing through sleeve sections arranged or secured 70 in the respective cup members. In this instance, the tie-rods 23 are dispensed with while the remaining parts of the silencer are of the construction shown in Fig. 4.

In use, the exhaust gases directed into the 75 silencer are gradually taken up by the respective cup members. As the opening in each successive cup member from the entrance to the exit end of the silencer is reduced in diameter, it will be obvious that 80 each cup will deflect a portion of the gas stream and particularly that portion disposed beyond the edge of its opening. This will create a whirl or circular movement in the concave portion of each cup member, as 85 indicated by the arrows in Fig. 3, and the outer edge of such whirling portion of gases will be gradually drawn through the inwardly opening channels 4 at the edge wall of the particular cup. This movement is 90 toward the inlet end of the silencer, and as noted the gases passing from said channels into the collection chamber are given within said chamber an exactly opposite movement or toward the outlet end. The whirling 95 movement within the cup members develops a centrifugal action which is continued until the expansive force of the gas overcomes the same at which time the gas finds its natural outlet through the channels 4. Therefore, 100 when the gases reach the collection chamber, they are moving practically under their expansive force alone.

It will be noted that the deflecting surface of the cup member at the outlet end of 105 the silencer has the maximum concaved surface so that the greatest volume of gas will naturally be handled at this point. As this particular cup member is more closely adjacent the outlet from the silencer it will be 110 obvious that such maximum volume of gas will tend to create a suction at the inlet end. Experience has demonstrated that such operation will tend in effect to create a vacuum at the inlet end of the silencer and thereby 115 draw all of the spent gases from the cylinder, not only scavenging the latter, but materially increasing the horse-power from a given charge and cylinder over the use of the ordinary muffler under the same condition, due primarily to the withdrawal of all 120 spent gases from the cylinder and insuring a perfect fresh charge for next explosion.

It is, of course, to be understood that any 125 desired number of cup members may be used and that the sizes of the adjacent deflecting surfaces may be varied with relation to each other to any desired extent.

Having thus described my invention, what I claim as new is:

1. A silencer including a series of deflecting members and a collection chamber encircling said members, the deflecting members each including a central opening and a concavo-convex deflecting surface arranged beyond the opening, and a final deflecting member arranged in alignment with the first-mentioned deflecting members and including a concavo-convex deflecting surface, and a wall bridging the opening formed by the aligned openings of the first-mentioned deflecting members. 10
2. A silencer including a series of deflecting members and a collection chamber encircling said members, the deflecting members each including a central opening and a concavo-convex deflecting surface arranged beyond the opening, and a final deflecting member arranged in alignment with the first-mentioned deflecting members and including a concavo-convex deflecting surface, and a wall bridging the opening formed by the aligned openings of the first-mentioned deflecting members, and means carried by each deflecting member to direct the current from the deflecting surface into the collection chamber. 20
3. A silencer made up of a series of deflecting members arranged in alignment and forming a central passage through the silencer, a final deflector corresponding to the remaining deflectors and formed with an imperforate wall to bridge the central passage in the deflector, each of said members including a concavo-convex deflecting surface, and a rearwardly extending edge wall, and a collection chamber encircling the deflecting members and receiving the gases between the edge walls of adjacent deflecting members. 30
4. A silencer made up of a series of concavo-convex deflecting members having rearwardly extending edge walls, said members being in part formed with a central opening and the final member provided with an imperforate wall in line with the remaining members, the openings of the successive members being gradually decreased in the direction of flow of the gases, and means carried by each deflecting member to cooperate with the similar means of the next succeeding member to direct the gases rearwardly with respect to their normal flow, and a suction chamber to receive said gases from the deflecting members. 40
5. A cup member having silencers including a body formed with a concavo-convex deflecting surface, and a convoluted edge flange. 50
6. A cup member having silencers including a body formed with a concavo-convex deflecting surface, and a convoluted edge flange projecting in approximate parallelism with the axis of the member. 65
7. A silencer including a series of aligned cup members, and a collection chamber encircling said members, each of said members being formed with a central opening, and a final cup member aligned with the other cup members and closing the passage formed by the central openings of the other cup members. 70
8. A silencer including a series of aligned cup members, and a collection chamber encircling said cup members, each of said cup members being formed with an edge wall of fluted configuration to provide a series of channels leading to the collection chamber. 75
9. A silencer including a series of aligned cup members, and a collection chamber encircling said cup members, each of said cup members being formed with an edge wall of fluted configuration to provide a series of channels leading to the collection chamber, and means for securing the cup members in interlocked relation. 80
10. A cup member for use in silencers including a concavo-convex bottom wall and a longitudinally fluted side wall. 90
11. A cup member for use in silencers including a concavo-convex bottom wall formed with a central opening and a longitudinally fluted side wall. 95
12. A cup member for use in silencers including a concavo-convex bottom wall and a longitudinally fluted side wall, said member at the juncture of the side and bottom walls being formed with integral projecting spurs 100 to engage the free edge of the side wall to the next adjacent cup.
13. A silencer including cup members having concavo-convex surfaces disposed at approximately right angles to the path of the incoming gases, and longitudinally fluted surfaces disposed in approximately parallelism with the path of the incoming gases. 105
14. A silencer including cup members, each having a concavo-convex surface disposed at an angle to the path of the incoming gases and a fluted surface disposed in approximately parallelism with the path of the incoming gases, the fluted surface of one cup overlying the fluted surface of the next adjacent cup. 110
15. A silencer including cup members, each having a concavo-convex surface disposed at an angle to the path of the incoming gases and a fluted surface disposed in approximately parallelism with the path of the incoming gases the fluted surface of one cup overlying the fluted surface of the next adjacent cup, the convolutions of one fluted surface registering with the opposing convolutions of the other fluted surface. 120
16. A silencer including cup members having concavo-convex surfaces disposed at ap- 125

proximately right angles to the path of the incoming gases, and longitudinally fluted surfaces disposed in approximately parallelism with the path of the incoming gases, the convolutions of the fluted surfaces opening in a direction opposite the direction of travel of the incoming gases.

In testimony whereof, I affix my signature in presence of two witnesses.
